William J. Tanner

UNITED STATES PATENT OFFICE.

WILLIAM J. TANNER, OF BRIDGEPORT, CONNECTICUT.

VIBRATION-GOVERNING DEVICE FOR SOUND-REPRODUCING MACHINES.

1,215,744.

Specification of Letters Patent. Patented Feb. 13, 1917.

Application filed January 9, 1914. Serial No. 811,205.

To all whom it may concern:

Be it known that I, WILLIAM J. TANNER, a citizen of the United States, and resident of Bridgeport, in the county of Fairfield 5 and State of Connecticut, have invented certain new and useful Improvements in Vibration-Governing Devices for Sound-Reproducing Machines, of which the following is a specification.

10 The invention consists of a device or attachment applicable to sound reproducing machines of various types but it is particularly useful with machines employing disk records. The object of the invention is to 15 provide means for obviating the disadvantages caused by excessive vibration of the stylus holder of the reproducer forming part of machines of this kind.

16 The improved device may permanently be 20 a part of the reproducer or it may be in the form of an attachment capable of being detachably secured to reproducers of various kinds employing a stylus carried by a holder, the latter having independent vibratory movement relatively to the main part 25 of the reproducer.

26 In accordance with the invention, the device or attachment consists essentially of 30 an arm suitably secured to the reproducer, and at the free end of the arm, a floating weight is carried. This weight is solid or it may be made hollow and to contain a liquid or a movable body, mercury preferably being employed. With either construction, the weight may be adjustably carried 35 on the arm, which arm is secured to the stylus or needle holder, this holder being mounted in a carrier generally so attached to the casing of the reproducer that, to a 40 limited extent, the carrier is allowed independent vibrating movement relatively to the reproducer casing.

41 The invention will be described in several forms hereinafter with reference to the accompanying drawings in which—

42 Figure 1 is an elevation of a complete reproducer with the improved device or attachment secured thereto;

43 Fig. 2 is a section taken on line *a—a* of Fig. 1, looking in the direction of the arrow;

44 Fig. 3 is a section taken on line *b—b* of Fig. 2 looking in the direction of the arrow;

45 Fig. 4 shows part of the reproducer in elevation and a solid weight in section, and Fig. 5 shows a modified means for secu-

ring the weight carrying arm to the needle holder of the reproducer.

46 Referring to the drawings, particularly Figs. 1, 2 and 3, 1 represents the reproducer; 2 is the needle holder mounted in the carrier 3; 4 is an arm composed of wire, resilient but not sensitive to slight vibration. The weight 5, carried at the end of the arm 4, is in the form of a closed cup containing 50 a movable body, for example mercury. The arm 4 is secured to the holder 2 by means of the frame 6 secured to the holder by set screw 7, the frame being slotted or cut away at 8 to clear the needle set screw 70 9. The weight 5 is screw threaded to the end of the arm in order that the weight may be adjusted to meet the requirements.

51 The purpose of the improved device is to eliminate the objectionable scratching or 75 rasping sounds caused by excessive vibration of the needle together with the parts adjacent thereto. This undesirable vibration prevents the needle point from always following the record groove exactly. Consequently an imperfect tone is produced and the life of the record is shortened owing to the wearing away of the walls of the groove. With the improved device a governing effect 80 is obtained and this effect is imparted to 85 the vibrating stylus holder of the reproducer, the greater vibrations being governed by the resiliency of the arm carrying the weight and the lesser vibrations being governed by the movable body within the 90 hollow weight. By means of this governing effect any vibration of the needle holder is controlled.

95 Fig. 4 illustrates a modified form of the invention, in which instance the weight 5 is solid and the arm 4 is composed of a flat spring sufficiently resilient so as to be sensitive to any vibration of the needle holder. Fig. 5 illustrates an alternative method of 100 securing the weight carrying arm direct to the reproducer. In this instance the end of the arm is screw threaded and fitted in a threaded hole in the needle holder 2 or if desired the arm may be attached to the carrier 3.

105 I am aware it has heretofore been proposed to employ a variety of forms of governing devices for sound reproducing machines, such devices having a rigid arm provided with a counter balance weight and 110 carrying the stylus or the arm is connected to the stylus holder. The arm is pivoted or

otherwise mounted in each instance, so that its movement is partly constrained, but according to my invention, the arm is resilient, therefore, the counterbalance weight has a floating or universal movement whereby the vibration is more effectually controlled, particularly lateral vibration, which causes most of the bad effects hereinbefore mentioned.

10. I claim—

1. In a sound reproducer for machines of the class described, a vibrating stylus holder, an arm secured thereto and a weight containing a movable body carried by said arm.
2. In a sound reproducer for machines of

the class described, a vibrating stylus holder, an arm secured thereto and an adjustable weight containing a movable body carried by said arm.

3. In a sound reproducer for machines of the class described, a vibrating stylus holder, a resilient arm secured thereto and a weight containing a movable body carried by said arm.

Signed at Bridgeport, in the county of Fairfield and State of Connecticut.

WILLIAM J. TANNER.
